UNITED STATES PATENT OFFICE.

JOHN D. DAUGHRILL, OF DETROIT, MICHIGAN.

MOLDING MACHINE.

Application filed July 13, 1925. Serial No. 43,263.

The device forming the subject matter of this application is a molding machine adapted to be used in the making of sand molds or casting operations. The machine disclosed in this application is an improvement on the molding machine shown in Patent No. 1,451,323, issued to me on the 10th day of April 1923. The object of the present invention is to provide novel means for handling the flask and the mold, after the mold has been formed; and, generally, to improve and to enhance the utility of devices of that sort to which the invention appertains.

Although a preferred form has been shown as a material embodiment of the invention, it will be understood that a mechanician, working within the scope of what is claimed, may make such changes as his skill 20 may suggest, without departing from the spirit of the invention.

In the accompanying drawings:—

Figure 1 shows in elevation, a device constructed in accordance with the invention, parts being in section; Figure 2 is a vertical section taken about on the line 2—2 of Figure 1; Figure 3 is a transverse section; and Figure 4 is a perspective view showing the table.

As hereinbefore stated, the machine of this application is constructed, in some respects like the machine shown in my Patent No. 1,451,323, and the description, therefore, may be shortened accordingly.

In carrying out the invention there is provided a frame which is denoted generally by the numeral 1. The frame 1 includes a platform 2 having an opening 3 extended inwardly from one edge of the platform. In top plan, the platform 2 is

of U-shape, as Figure 3 will disclose. A support 4, in the form of a pallet is provided, and is located in the opening 3. A shaft 5 extends transversely of the support 4, beneath the support, and is secured at 6 to the support. The ends of the shaft 5 are journaled in bearings 7 mounted on the undersurface of the platform 2 at opposite sides of the opening 3. The support 4 carries a pattern 8. A flask 9 is held by dowel pins 10, or otherwise, on the support 4. The rear portion of the support 4 rests on stops 11 carried by the platform 2. The stops 11 are located on one side of the shaft 5, as shown in Figure 3. A latch 12 is mounted for reciprocation on the platform

2, and engages the support 4 on the opposite side of the shaft 5 from the stops 11. The construction is such that the support is held in a horizontal position, but, at the will 60 of an operator, by retracting the latch 12, the support 4 may be reversed with the shaft 5 as an axis of rotation.

The numeral 14 designates a horizontal table provided at one end with an upstanding keeper 15. The table 14 is carried by a bracket 16 provided with a standard 17 disposed about at right angles to the table 14. The standard 17 is mounted to rotate and to slide endwise in bearings 18 mounted 70 on the frame 1. The table 14 is located below the platform 2 and the support 4. A handle 19 on the forward edge of the table affords a means whereby the table may be swung horizontally by an operator. In 75 order to hold the table 14 against horizontal swinging movement, after it has been elevated, the frame 1 is provided with a spring latch 20 adapted to cooperate with the keeper 15 on the table 14. The table 80 14 is equipped with depending wear plates 21. The wear plates 21 are adapted to be engaged by the upper ends of plungers 22 which are supported at 23 for vertical sliding movement in the frame 1. Rollers 24 85 are journaled on the lower ends of the plungers 22 and are adapted to cooperate with cams 25 on a tubular shaft 26 mounted to rotate on a shaft 27 which, in its turn, is journaled in bearings 28 on the frame 90 1. The tubular shaft 26 carries a laterally and upwardly extended handle 29 which moves at one side of the frame. The handle 29 is shown as somewhat short in the drawing, but the handle may be of any desired 95 length.

At its ends, the shaft 27 has cranks 30. The lower ends of pitmen 31 are pivotally mounted on the cranks 30. The upper ends of the pitmen 31 are pivotally mounted on 100 the ends of a cross head 32. The cross head 32 is guided for reciprocation, vertically, in the upper portion of the frame 1, and is located above the platform 2. The numeral 34 marks a ram provided with a pattern 35 which moves above the pattern 8 of the support 4. The ram 34 carries posts 36 passing through the cross head 32. Nuts 37 are threaded on the posts 36 and engage the upper and lower surfaces 110 of the cross head 32. The nuts 37 constitute means whereby the ram 34 may be

adjusted vertically with respect to the cross head 32. The upper ends of the posts 36 of the ram 34 are slidably mounted in the upper part of the frame 1, as indicated in Figure 1.

In order to impart rotation to the shaft 27, the same is supplied with a crank arm 38 to which the lower end of a link 39 is pivoted. The upper end of the link 39 is pivoted to an operating member, such as a lever 40, the lever being fulcrumed intermediate its ends, at 41, on the upper part of the frame 1.

The support 4 is held in the horizontal position shown in the drawings by stops 11 and the latch 12. The flask 9 is mounted on the support 4. The sand 43 is placed in the flask 9. Through the instrumentality of the lever 40, the link 39, the crank arm 38, the shaft 27, the cranks 30, the pitmen 31, the cross head 32 and the posts 36, the ram 34 is brought downwardly upon the sand 43 in the flask 9, and the sand 43 receives the impress of the patterns 8 and 35. By means of the lever 40 and coacting parts, the ram 34 is lifted from the flask 9. The latch 12 is retracted from engagement with the support 4, and the support 4 is reversed on an axis represented by the shaft 5, so that the flask 9 is located below the support. The table 14 is swung horizontally, the standard 17 rotating in the bearings 18. In this way, the table 14 is brought beneath the flask 9 which has been inverted, along with the table 14. By way of the handle 29, the shaft 26 is rotated, and the cams 25 elevate the plungers 22, the plungers cooperating with the wear plates 21 to elevate the table 14 up to the inverted flask 9, the standard 17 sliding vertically in the bearings 18. The clamping means 42 are released, leaving the flask 9 and the molded sand on the table 14, whereupon the table may be lowered, by a manipulation of the handle 29, the table then being swung outwardly into the position shown in dotted line in Figure 3 to carry the flask and the mold clear out of the machine. The flask and the mold then may be lifted off the table 14 and be carried to any position where they are to be used.

Any suitable means may be provided for holding the flask 9 on the support 4, whilst the support is being reversed. Thus, recourse may be had to a U-shaped yoke 50 extended beneath the support 4 and provided in its upright arms with slots 51 which receive the shaft 5, so that the yoke 50 can be moved vertically. The arms of the yoke 50 have extensions 52 terminating in hooks 53, turnbuckles 54, or like adjusting devices, being interposed in the extensions 52. The hooks 53 are adapted to receive, removably,

a holder 55, such as a rod, shown in dotted line in Figure 1, the rod 55 extending across the flask 9. A cam lever 56 is mounted at 57 for swinging movement on the intermediate portion of the yoke 50 and is adapted to cooperate with one of the connections 6 which unites the shaft 5 with the support 4.

It will be clear that, by operating the cam lever 56, the yoke 50 will be moved downwardly, thereby causing the rod 55 to hold the flask 9 on the support 4.

Having thus described the invention, what is claimed is:—

1. In a device of the class described, a frame, a table, a support, means for holding a flask on the support, means for mounting the support on the frame for reversal with respect to a horizontal axis, means for mounting the table on the frame for horizontal swinging movement and for vertical sliding movement to permit the table to be swung beneath the support and to permit the table to be raised with respect to the support, when the support is reversed; and a ram movable on the frame and located above the support.

2. A device of the class described, constructed as set forth in claim 1, and further characterized by the provision of mechanism for operating the ram and mechanism for raising the support, each mechanism including a shaft, and one shaft being mounted to rock upon the other shaft.

3. In a device of the class described, a frame, a table, a support, means for holding a flask on the support, means for mounting the support on the frame for reversal with respect to a horizontal axis, means for mounting the table on the frame, for horizontal swinging movement, and for vertical sliding movement to permit the table to be swung beneath the support and to permit the table to be raised with respect to the support, when the support is reversed; and mechanism for raising the table, said mechanism including a plunger slidable in the frame and cooperating with the table, a shaft, means for operating the shaft, means for mounting the shaft on the frame for rocking movement, and a cam carried by the shaft and coacting with the plunger.

4. A device of the class described, constructed as set forth in claim 1, and further characterized by the fact that the first-specified means embodies a movable yoke, a flask-engaging holder assembled with the yoke, and means for operating the yoke to cause the holder to cooperate with a flask.

In testimony that I claim the foregoing as my own, I have hereto affixed my signature.

JOHN D. DAUGHRILL.
